UNITED STATES PATENT OFFICE.

HANS HOFER, OF ZUG, SWITZERLAND, ASSIGNOR TO VERZINKEREI ZUG A. G., OF ZUG, SWITZERLAND.

CENTRIFUGAL MACHINE FOR TREATING METAL ARTICLES COATED BY IMMERSION.

Application filed November 30, 1926, Serial No. 151,817, and in Great Britain September 23, 1926.

This invention is an improvement in and relating to centrifugal machines of the type having an electric motor, a shaft driven by this motor and a container for receiving 5 metal articles coated by immersion and to be freed from superfluous coating metal by the action of the centrifugal force, the said container being capable of being driven by the said shaft.

10 According to the present invention the arrangement is such that the shaft which is driven by the electro-motor can be turned by hand as well.

In the accompanying drawing a constructional example of the invention is shown:

Figure 1 being a vertical section through the lower part of the centrifugal machine;

Figure 2 an axial horizontal section through the arrangement for driving the 20 centrifugal machine by hand, and

Figure 3 a diagrammatic view of the latter.

1 is an electro-motor mounted on the vertical shaft 12, 2 is a casing surrounding the 25 motor, 6 a brake for the motor shaft, 13 the driving basket mounted on the upper end of the motor shaft and adapted to support a perforated container for receiving metal articles coated by immersion and to be freed 30 from superfluous coating metal by the action of the centrifugal force. 7 is a protective hood which is suspended from a rope provided with a counterpoise.

On the shaft 12 a bevel wheel 3 is fixed, 35 which meshes with a bevel wheel 4 fixed on a horizontal shaft 5, (Figs. 2 and 3). At the outer end of the shaft 5 a spur wheel 8 is fixed, which meshes with internal teeth 17 on a hand wheel 9. The wheel 9 is mounted loosely on the eccentric part 10 of a stub shaft 11 which is mounted so as to be 40 capable of turning in an extension 14 of the casing 2, but which can be fixed by means of a screw 18.

45 A cap nut 16 which is screwed on to a threaded part of the stub shaft 11 prevents

any axial motion of the hand wheel 9, but allows it to turn on the journal 10.

The eccentricity of the journal 10 is such that in one position of the stub shaft 11 the 50 spur wheel 8 and the internal tooth 17 of the hand wheel 9 are in engagement with one another, while a rotation of the stub shaft 11 through 90° will displace the hand wheel radially to such an extent that its internal teeth 17 will cease to engage with the spur wheel 8 (see Fig. 3 and the dot and dash lines in Fig. 2). In the former case the motor shaft 12 can be driven by means of the hand wheel. In the second case, the 55 hand wheel remains stationary, even when the motor 1 is running. For turning the journal 10 a key not shown may for instance be used, the key being adapted for engagement with two diametrically opposite holes 16' on the external side of the nut 16. For limiting the rotary motion of the journal 10 a screw 15 is provided, the inner end of which extends into a circumferential groove 65 in the stub shaft 11 and acts as a stop for the latter when being turned.

What I claim is:—

A centrifugal machine including a frame, a vertical shaft mounted therein, means for receiving the materials to be treated mounted 75 on this shaft, a stationary stub shaft mounted on said frame capable of adjustment in the circumferential direction within certain limits and having an eccentric part, a wheel rotatably mounted on this eccentric part, internal teeth on the wheel, a toothed wheel mounted within the wheel and with which toothed wheel the internal teeth on the wheel can be brought into and out of engagement by a rotating movement of the 80 stub shaft within the above mentioned limits, a shaft connecting said internal toothed wheel with a gearing which connects this shaft with the driving shaft.

In testimony whereof I have affixed my 90 signature.

HANS HOFER.
